UNITED STATES PATENT OFFICE.

JOHN BLASIUS, OF UNION, NEW JERSEY.

SASH-FASTENER.

SPECIFICATION forming part of Letters Patent No. 574,876, dated January 12, 1897.

Application filed February 28, 1896. Serial No. 581,102. (No model.)

To all whom it may concern:

Be it known that I, JOHN BLASIUS, a citizen of the United States, and a resident of the town of Union, in the county of Hudson and State 5 of New Jersey, have invented certain new and useful Improvements in Locks or Fastening Devices for Window-Sashes, of which the following is a specification, reference being had to the accompanying drawings, forming a part 10 thereof, in which similar letters of reference indicate corresponding parts.

This invention relates to window-locks, or to fastening devices for the sashes thereof; and the object of the invention is to provide 15 an effective device of this class by means of which the upper and lower sashes may be locked together, a further object being to provide such a device which is simple in construction and operation and comparatively 20 inexpensive.

The invention is fully disclosed in the following specification, of which the accompanying drawings form a part, in which—

Figure 1 is plan view of my improved lock 25 or fastening device, showing the same connected with the upper and lower sashes; Fig. 2, a side view thereof, showing a portion of the upper and lower sashes in section; Fig. 3, a plan view of that part of the lock which 30 is connected with the lower sash, the top plate being removed; Fig. 4, a section on the line 4 4 of Fig. 3; Fig. 5, a plan view of a modified form of my improved lock; Fig. 6, a section thereof on the line 6 6, and Fig. 7 a side 35 view of that part of the lock or fastening device which is connected with the upper sash.

In the practice of my invention I provide a lock or fastening device which consists of two parts, one of which is connected with the 40 lower cross-bar A of the upper sash and the other with the upper cross-bar of the lower sash.

That part of the fastening device which is secured to or connected with the upper sash 45 is shown in plan view in Fig. 1 and in side view in Fig. 7, and consists of a plate B, on which is formed a central upwardly-directed portion b, at the sides of which are formed notches or recesses b², and in the top of which 50 is formed a transverse slot b³.

That part of the lock which is connected with the lower sash consists of a plate D, with

which are connected two pivoted levers d, which are pivoted at d², and between which is placed a yoke-spring E, the ends of which bear 55 against the outer ends of said levers, and the inner ends of said levers are adapted to enter the notches or recesses b² and that part of the lock which is secured to the upper sash.

A cross-bar d³ is secured to the plate D between the inner ends of the levers d, so as to prevent the same from coming too close together, and between the outer ends of said levers d is a cross-head G, the ends of which are inclined in opposite directions and are 60 adapted to abut against the inclined shoulders or projections g, formed on the levers d, and passing through the cross-head G is a bolt or shaft H, the upper end of which is provided with a cross-head or yoke h, and 65 that part of the bolt or shaft which passes through the cross-head G is square or many-sided in form, and over the levers d, the cross-head G, and the spring E is placed a top plate K, which is held in place by screws k, which 70 form the pivotal connection of the levers d, and the outer ends of said levers are provided with outwardly-directed arms M, which are provided with heads m, and the inner end of the top plate or cover K is provided centrally 75 with a vertical shoulder or extension O, which is formed thereon or secured thereto, and on the outer end of which is formed a projection O², which is adapted to enter the transverse slot b³ in the part secured to the upper sash, 80 and the form of this shoulder or projection O² and the transverse slot b³ is such as to 85 make a tongue-and-groove connection, whereby the sashes are drawn together and the rattling thereof prevented.

The top plate or cover K is provided near its inner end with a depending shoulder or projection k³, in the lower end of which is formed a groove which incloses the cross-head of the yoke-spring E, as shown in Fig. 90 4, whereby said spring is held in position, and the operation of this form of construction will be readily understood from the foregoing description when taken in connection with the accompanying drawings and the following 95 statement thereof.

In order to disconnect the sashes, it is only necessary to turn the cross-head G by means of the handle h of the shaft H and to press

- inwardly on the heads *m* of the arms *M*, and this operation forces inwardly the outer ends of the levers *d* and forces outwardly the inner ends thereof, whereby they are disconnected 5 from the plate *B*, which is secured to the upper sash, and the lower sash may then be raised and the upper sash lowered if desired, and by reversing this operation said sashes may be again locked together.
- 10 In the construction shown in Figs. 5 and 6 the shoulder or projection *O*² on the top plate or cover *K* is of the form in longitudinal section shown in Fig. 6, and the plate or part *B*, which is secured to the upper sash, is provided with an upwardly-directed shoulder or projection *P*, the inner side of which is inclined, and the outer side of the shoulder or projection *O* is similarly inclined, and by means of this arrangement, when the sashes 15 are locked together by the levers *d*, they are also drawn together laterally by the shoulders or projections *O*² and *P*, and the operation of this form of construction will be substantially the same as that hereinbefore described.
- 20 It will thus be seen that I provide a locking device for the sashes of windows which is simple in construction and operation and which is perfectly adapted to accomplish the result for which it is intended, and it is evident that changes in and modifications of the 25 construction herein described may be made

without departing from the spirit of my invention or sacrificing its advantages.

Having fully described my invention, I claim as new and desire to secure by Letters 35 Patent—

A lock or fastening device for window-sashes, which is composed of two parts, one of which is adapted to be secured to the upper sash, and the other to the lower sash, that 40 part which is adapted to be secured to the upper sash being provided with notches or recesses in the sides thereof, and with a dovetailed cross-groove in the top thereof, and that part which is adapted to be secured to 45 the lower sash being provided with spring-operated levers which are adapted to enter said notches or recesses, and said part being also provided with a shoulder or projection which is adapted to enter the said dove-tailed groove, and with means for operating said levers, substantially as shown and described.

In testimony that I claim the foregoing as my invention I have signed my name, in presence of the subscribing witnesses, this 10th day of February, 1896.

JOHN BLASIUS.
